PRINTING TELEGRAPH CONTROL MECHANISM

Walter S. Lemmon, New York, N. Y., assignor to
International Business Machines Corporation,
New York, N. Y., a corporation of New YorkApplication October 2, 1934, Serial No. 746,489
Renewed December 1, 1937

13 Claims. (Cl. 178—23)

This invention relates to printing telegraph control mechanism and is particularly adapted to control the receiver units in a distinctive manner upon the reception of successive electrical impulses, the characteristics of which are the same. More particularly the invention relates to key control mechanism comprising a double step relay, and an object of which is to provide means to be actuated by successive electrical impulses, having similar characteristics, the first of which causes an electrical control switch to be operated which remains in said operative position, and the second of said impulses causes the electrical switch to return to its normal inoperative position.

This feature when particularly applied to the case shift mechanism is extremely useful and important in that separate shifting and unshifting control mechanisms are eliminated.

Various other objects and advantages of my invention will be obvious from the following particular description of one form of mechanism embodying the invention or from an inspection of the accompanying drawing, and the invention also constitutes certain new and novel features of the construction and combination of parts hereinafter set forth and claimed.

In the drawing:

Fig. 1 is a fragmentary sectional elevation illustrating a portion of the recording unit.

Fig. 2 is a schematic circuit diagram.

Fig. 3 is a side view of the double step relay.

Fig. 4 is an elevational view of the relay.

The invention can be embodied in a considerable variety of constructions, and of these one has been selected for specific description and illustration herein the one which at the present time is believed to exhibit the invention in its most convenient and effective form. The construction referred to is one form of power driven recording units particularly adaptable to printing telegraph systems and described in my co-pending application Serial No. 677,018 filed June 22, 1933.

Referring now to the drawing in which similar parts are designated by the same numerals in the several views, it is believed that a clear understanding of the invention will be had therefrom when considered in conjunction with the following description.

For the sake of clarifying the following description, the operation of the recording unit will be given first, followed by a description of the operation and of the parts of the double step

relay necessary for a full understanding of this invention.

Recording mechanism

As mentioned before for illustrative purposes, this invention is shown as embodying a power driven typewriter of the type disclosed in the aforesaid application, the construction of which is well known to those in the art, and hence requires only the following brief description.

Referring now to Fig. 1, in the embodiment illustrated in the drawing, well known means are provided for actuating the type bars and case shift mechanism by power operated devices comprising a power driven roller 10.

A cam 11 is pivoted on one arm of a bell crank lever 12 pivoted in the frame, the other arm of which is operatively connected with one arm of a bell crank lever 13 by means of link 14. The other arm of lever 13 is connected to the type bars (not shown) in a well known manner and fully disclosed in the aforesaid application.

The lever 12 is actuated by the cam 11 when the latter engages the driven roller 10 to be operated thereby. The engagement of the cam 11 with the power roller is controlled automatically by means of the solenoid 18 connected to the key bar 17 by link 19. The cam 11 is resiliently engaged by a spring-pressed arm 20 which tends to turn it into engagement with the power driven roller or a stop 21 on a lever 22 pivoted on the bell crank 12 and normally arranged in the path of a lug 23 on the cam. When the lever 22 swings to move its stop out of the path of the lug, the arm 20 swings the cam into engagement with the power roller to be actuated thereby to swing the bell crank 12 to actuate its connected mechanism. The lever 22 has an arm 24 which is provided with an offset projection 25 at its end which projects laterally through an opening 35 in the bell crank 12 and engages the bifurcated lower end 26 of an arm 27 of a key lever 17 pivoted on the common rod 28 and linked to the solenoid 18. It is obvious then that energization of solenoid 18 in causing a key lever 17 to be depressed releases the revolubly mounted cam 11 to engage and be actuated by power roller 10 in turn operating bell crank 12 and its attached links to cause the associated mechanism such as the key bars or case shift mechanism to be operated.

One of the links 16 connected to a bell crank 12 is associated with the case shifting mechanism (not shown) well known in the art and a disclosure of which is given in U. S. Patent 1,945,097 issued to R. G. Thompson, et al., January 30, 1934.

so that further description is not necessary since the case shifting mechanism itself is not claimed as part of this invention. It is understood that the case shift mechanism remains in its operated position so long as the controlling key bar 17 is depressed which is the common practice.

Double step relay

Referring now to Figs. 3 and 4 illustrating one form of a double-step relay the function of which is to control the key lever mechanism for example, the case shift lever mechanism so that it remains in its operative position upon the reception of a particular impulse and to be rendered inoperative upon the receipt of a second impulse having the same characteristics.

The relay comprises a magnet 30 which, upon energization, will rock its armature 31 to which is attached an extension arm 32 and pivotally mounted at 33. Arm 32 also carries at its free end a pawl 34 which is pivoted thereto and pressed by a spring 35 into engagement with a ratchet 36 having 20 teeth. A leaf spring member 37 fastened to the frame 38 serves as a detent 25 to hold ratchet 36 in position. Rocking of armature 31 will cause the arm 32 to be moved to the right as viewed in Fig. 3, which upon de-energization, is urged by spring 39 attached to arm 32 and member 40 to advance ratchet 36 one tooth.

Member 40 is rigidly fixed to an extension 41 of frame 38. Ratchet 36 is mounted upon a rod 42 mounted on frame 38 and which also carries a slotted cam 43 having half the number of slots 35 as teeth in the said ratchet. Cooperating with the cam 43 are contacts 44 adapted to be closed when the high surfaces of cam 43 are engaged. Since ratchet 36 has 20 teeth and cam 43 has 10 high surfaces, it is obvious that a single operation 40 of magnet 30 will close contacts 44 and a second energization of the magnet will permit them to resume the position they occupy in Fig. 3. The function of contacts 44 will be fully explained in connection with the circuit diagram.

45

Operation

Referring to Fig. 2, magnet 30 is shown as adapted to be connected to a printing telegraph line or radio network suitable to receive single characteristic impulses. Upon the receipt of the first impulse contacts 44 are adapted to be closed as fully explained above to cause the circuit 45 to energize the solenoid 18 connected to key lever 17. Closure of contacts 44 causes the condenser 46 to discharge through the windings of solenoid 18 to overcome initial inertia of solenoid 18 and during the remaining period of energizing the said solenoid preventing a short circuit of the current mains 47. Energization of solenoid 18 60 in the manner just described causes a key lever 17 to be depressed to release the cam 11 and then actuated by power roller 10 to rotate the cam a half revolution which causes the bell crank lever 12 to operate its connected mechanism, preferably the case shift mechanism through the connecting link 16.

The case shift mechanism will remain in this operated position during the period solenoid 18 remains energized. Upon reception of the second impulse contacts 44 are caused to be opened to break the local circuit 45 to deenergize solenoid 18 releasing its connected key lever 17 to restore the case shift mechanism to its original position.

While there has been shown and described and 75 pointed out the fundamental novel features of

the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a printing telegraph recording unit, operating instrumentalities, power operated devices individual to said instrumentalities, a plurality of keys each adapted to cause actuation of one of the power operated devices, means for operating said keys, and means to control said key operating means, said control means adapted to function in a different manner upon successive operations thereof.

2. A printing telegraph recording unit comprising case shift instrumentalities, power operated devices individual to said instrumentalities, a key adapted to cause actuation of said power operated device, control means for operating said case shift key, and means to operate the said key alternately automatically upon successive operations of the said control means.

3. In a printing telegraph recording unit, the combination of a case shift mechanism, a power driven roller, a cam movable into operative engagement with said roller for actuating said case shift mechanism, a movable key lever for controlling the engagement of said cam with the power driven roller, electromagnetic means for operating said case shift key lever, and means comprising an electromagnetically controlled switch to operate the said key alternately upon successive operations of the last named means.

4. In a remotely controlled recording mechanism, the combination of an operating instrumentality, a power operated device individual to said instrumentality, a key lever adapted to cause actuation of said power operated device, means for operating said key lever, a circuit adapted to be energized by successive impulses, and means included in said circuit to control the operation of said key lever whereby the associated power operated device is controlled in a different manner upon successive energization of said circuit.

5. In a remotely controlled recording mechanism, the combination of an operating instrumentality, a power operated device individual to said instrumentality, a key lever adapted to cause actuation of said power operated device, means for operating said key lever, a circuit adapted to be energized by successive impulses having the same characteristics, and means included in said circuit comprising electromagnetic means to control the operation of said key lever whereby the associated power operated device is controlled in a different manner upon successive energization of said circuit.

6. In a remotely controlled recording mechanism, the combination of an operating instrumentality, a power operated device individual to said instrumentality, a key lever including controlling means adapted to cause actuation of said power operated device, a circuit adapted to be energized by successive impulses, and means included in said circuit comprising a double step relay to control the operation of said key lever whereby the associated power operated device is controlled in a different manner upon successive energization of said circuit.

7. In a remotely controlled recording mecha-

75

nism, the combination of an operating instrumentality, a power operated device individual to said instrumentality, a key lever including controlling means adapted to cause actuation of 5 said power operated device, a circuit including means adapted to be energized by successive impulses, means adapted to be actuated in a definite manner by said impulses, means associated with last named means to cause said key lever controlling means and operating instrumentality to become operative upon energization of said means included in the circuit, and means to cause said key lever controlling means and operating instrumentality to become inoperative 10 upon the successive energization of said means included in the circuit.

8. In a remotely controlled recording mechanism, the combination of an operating instrumentality, a power operated device individual to 20 said instrumentality, a key lever including controlling means adapted to cause actuation of said power operated device, a circuit including means adapted to be energized by successive impulses, means adapted to be operated in a 25 similar distinctive manner by each of said impulses, means controlled by the last named means to cause said controlling means and operating instrumentality to become operative and inoperative respectively upon successive 30 energization of said means included in the said circuit.

9. In a remotely controlled recording mechanism, the combination of an operating instrumentality, a key lever including controlling means 25 adapted to cause operation of said instrumentality, a circuit including means adapted to be energized by successive impulses at all times, operating means controlled by the energization of the said means included in the circuit, and 40 means connected at all times to said controlling means and cooperating with the said operating means to operate the said controlling means

whereby the associated power operated device is controlled in a different manner upon the successive energization of the said means included in the circuit.

10. In a remotely controlled recording mechanism, the combination of an operating instrumentality, a key lever including controlling means adapted to cause operation of said instrumentality, and means adapted to operate the key lever controlling means including means rendered 10 operative and inoperative upon successive operation of the second mentioned means.

11. In a remotely controlled recording mechanism, the combination of an operating instrumentality, a key lever and control means therefor adapted to cause operation of said instrumentality, and electromagnetic means adapted to control the operation of the key lever, including means connected at all times to said control means, whereby the said instrumentality is controlled in a different manner upon successive energization, at all times, of said electromagnetic means.

12. In a remotely controlled mechanism, the combination of an operating instrumentality, a 25 lever to actuate said instrumentality, electromagnetic means cooperating with said lever to operate the lever upon its energization and de-energization respectively, and operable means to control the energization of the said electromagnetic means upon successive operation of the 30 said operable means.

13. In a remotely controlled mechanism, the combination of an operating instrumentality, a lever to actuate said instrumentality, electromagnetic means cooperating with said lever to operate the lever upon its energization, and a 35 relay adapted to control the energization and deenergization respectively of said electromagnetic means upon successive operation of the 40 said relay.

nism, the combination of an operating instrumentality, a power operated device individual to said instrumentality, a key lever including controlling means adapted to cause actuation of 5 said power operated device, a circuit including means adapted to be energized by successive impulses, means adapted to be actuated in a definite manner by said impulses, means associated with last named means to cause said key lever controlling means and operating instrumentality to become operative upon energization of said means included in the circuit, and means to cause said key lever controlling means and operating instrumentality to become inoperative 10 upon the successive energization of said means included in the circuit.

8. In a remotely controlled recording mechanism, the combination of an operating instrumentality, a power operated device individual to 20 said instrumentality, a key lever including controlling means adapted to cause actuation of said power operated device, a circuit including means adapted to be energized by successive impulses, means adapted to be operated in a 25 similar distinctive manner by each of said impulses, means controlled by the last named means to cause said controlling means and operating instrumentality to become operative and inoperative respectively upon successive 30 energization of said means included in the said circuit.

9. In a remotely controlled recording mechanism, the combination of an operating instrumentality, a key lever including controlling means 25 adapted to cause operation of said instrumentality, a circuit including means adapted to be energized by successive impulses at all times, operating means controlled by the energization of the said means included in the circuit, and 40 means connected at all times to said controlling means and cooperating with the said operating means to operate the said controlling means

whereby the associated power operated device is controlled in a different manner upon the successive energization of the said means included in the circuit.

10. In a remotely controlled recording mechanism, the combination of an operating instrumentality, a key lever including controlling means adapted to cause operation of said instrumentality, and means adapted to operate the key lever controlling means including means rendered 10 operative and inoperative upon successive operation of the second mentioned means.

11. In a remotely controlled recording mechanism, the combination of an operating instrumentality, a key lever and control means there- 15 for adapted to cause operation of said instrumentality, and electromagnetic means adapted to control the operation of the key lever, includ- 20 ing means connected at all times to said control means, whereby the said instrumentality is controlled in a different manner upon successive energization, at all times, of said electromagnetic means.

12. In a remotely controlled mechanism, the combination of an operating instrumentality, a 25 lever to actuate said instrumentality, electro- 30 magnetic means cooperating with said lever to operate the lever upon its energization and de-energization respectively, and operable means to control the energization of the said electro- 35 magnetic means upon successive operation of the 40 said operable means.

13. In a remotely controlled mechanism, the combination of an operating instrumentality, a lever to actuate said instrumentality, electro- 35 magnetic means cooperating with said lever to operate the lever upon its energization, and a relay adapted to control the energization and deenergization respectively of said electromagnetic means upon successive operation of the 40 said relay.
